MEANS FOR POLISHING SPACEBANDS

Arthur A. Rock, deceased, late of Wauwatosa,
Wis., by Monica Rock, executrix, Wauwatosa,
Wis.

Application August 19, 1936, Serial No. 96,710

3 Claims. (Cl. 51—110)

The invention relates to improvements in space-band cleaning machines, and more particularly to the type of machine shown in the patent to William H. Schuyler and George J. Chiles, No. 5 1,388,767.

An object of the invention is to provide improved means of supplying graphite to the space-bands for the polishing of the same.

Another object is to provide improved means 10 of imparting power to the space-band handling apparatus.

Another object is to provide improved means for assembling the space-bands in stacked relation after the cleaning operation.

15 Other and further objects will appear as the description proceeds, reference being had to the accompanying drawings, in which:—

Fig. 1 is a side view partly in elevation and partly in section of a space-band cleaning machine embodying the invention.

Fig. 2 is a plan view similar to Fig. 1.

Fig. 3 is a view taken on line 3—3 of Fig. 1.

Fig. 4 is a view taken on line 4—4 of Fig. 1.

20 Fig. 5 is a fragmentary side view partly in elevation and partly in section, showing the release key means.

Fig. 6 is a perspective view of a conventional space-band.

Referring more particularly to the drawings, 25 the numeral 10 represents a frame having conventional legs, 11, 12, 13, and 14. Supported in said frame at 15 and 16 thereof, is a conventional electric motor, 17, connected by a coupling 18 with a shaft 19, journaled at 20 of the frame 10, 30 and having fixed thereon the worm 21, which is meshed with the worm wheel, 22, to which latter is affixed the vertical shaft 23 mounted in the journal bearing 24, and supporting at its upper end the turn table 25. The vertical shaft 23 is 35 journaled at its lower end in the bearing 26 carried by the assembling plate 27. The said shaft 23 carries adjacent to the lower end thereof, a worm, 28, which is meshed with the worm wheel 29, to which is affixed the crank 30, which latter 40 actuates a sleeve 31, freely sliding on the pivot arm 32. The latter is pivoted at 33 with the connecting rod 34, which is in turn pivoted to the feed drive shaft 35 which is secured by means 45 36 to the depending arm 37 coupled by threaded means 38 to the feed bars 39 and 40.

The turn table 25 has an upper surface adapted for polishing. A magazine 41 is provided for retaining space-bands in stacked relation and holding them in readiness for withdrawal onto the said turn-table by the action of the feed bars. 50

An automatic feed plate, 42, has affixed thereto a hopper, 43, for dispensing graphite, 44, to the spacebands as they are released. A bracket 45 attached to one of the guide-ways 46 supports a hopper, 47, which also contains graphite for distribution to the surface of the polishing turntable, 25.

An assembling container 48 is affixed to the bracket 45, which latter also is the base for the upstanding arm 50 holding the adjustable release 10 pin 51. Feed bars 39 and 40 carry at their ends adjacent the turn-table 25, the plunger housing 52, inside of which is the coiled expansion spring 53 adapted to actuate the plunger 54. A rubber disk 55 is affixed in the recess 56 of said plunger. 15

The plunger 54 is slotted longitudinally at 57 to accommodate the key 58 having the cam surface 59. A pin 60 held within the slotted portion of the plunger 54, carries the roller 61. The feed bars 39 and 40 carry the lugs 62 which push 20 against the ends 63' of space-bands 64 in the operation of the machine.

The automatic feed plate 42 is provided with slots, 65, and is held slidingly against the magazine 41 by means of bolts 66 engaging in said 25 slots. Springs 67 are provided to hold plate 42 normally downwardly pressing against the cover plate 68. The lower edge of plate 42 is beveled to permit an oncoming space-band 64 to force it upwardly for admission on to the turn-table of 30 the latter.

In operation, a plurality of the space-bands is placed in the magazine 41. The motor 17 simultaneously revolves the turn-table 25 and reciprocates the guide bars 39 and 40. The rotation of shaft 19 revolves the worm 21, turning vertical shaft 23 by means of worm wheel 22. The worm 28 on the lower end of vertical shaft 23 revolves the worm wheel 29 and crank 30 to reciprocate the sleeve 31, thus in turn reciprocating the pivot 40 shaft 32, the connecting rod 34, the feed drive shaft 35 and the feed guides 39 and 40. The feed guides, in traveling toward the turn-table 25, impinge with the lugs 62, the end 63' of the lowermost space-band 64, forcing it under the 45 feed plate 42, which latter is spring-loaded to press normally downwardly, and place a space-band partly over the table 25. When the guide bars return outwardly of the turn-table the contact of key 58 with the feed plate 42 pushes said 50 key forwardly allowing the roller 61 to roll downwardly over cam surface 59 to permit spring 53 to force the plunger 54 downwardly, thus forcing the space-band, previously placed in position, against the polishing surface of the turn-table, 55

and the later forward movement of the feed bars and attached plunger will carry the space-band across the revolving polishing surface. It will be understood that the downward pressure of the feed plate on the approximate center of the space band 64 will prevent the latter from being thrown out of the machine until it is gripped by the plunger 54. As one space-band 64 is moved across the turn-table, the next in the stack is pushed out in position to be engaged by the plunger, by means of the lugs 62. To properly restack the space-bands after the operation of polishing the container or receptacle 49 is provided, having an arcuate inner bottom surface 69 and a substantially vertical inner end rib 70 to engage between the feet of the space-bands as they are forced into the container.

Having thus described the invention, what is claimed and desired to be secured by Letters

20 Patent of the United States, is:—

- 20 1. A device of the class described comprising a base member, an electric motor housed therein, a horizontal shaft connected with said motor and journaled in the base, a worm fixed on said shaft, a vertical shaft, a gear on said vertical shaft meshed with said worm, a worm on said vertical shaft, a gear meshed with said vertical shaft worm, a crank fixed to said gear, an arm pivoted adjacent the bottom of said base, a sleeve 30 freely sliding on said arm and pivotally connected with said crank, a pair of parallel feed bars adapted to slide above and horizontally of the base, a depending coupling attached to the outer end of said feed bars, a feed drive shaft extending from said coupling inwardly toward the base and journaled to slide therein, a connection rod pivotally attached between said feed drive shaft and the sleeve driven pivot arm, a turn-

table fixed to the upper end of said vertical shaft, a polishing surface on said turn table, a magazine for space-bands to be cleaned, a vertical feed plate normally held downwardly by coil springs and having a bevelled edge whereby it is lifted as 5 the space-bands are successively forced thereunder, a hopper having abrasive material attached to said feed plate and having a restricted opening at the lower end thereof whereby the forceable return downwardly of the feed plate by 10 the springs will dislodge portions of said abrasive material, and means on the inner ends of said feed bars for drawing the said space bars successively across the polishing surface of said turn-table.

15 2. In a device of the class described a pair of feed bars slideable in housings therefor, a pair of lugs on said feed bars adapted to impinge against the lowermost of a stack of space-bands, a magazine between said housings for retention 20 of said space-bands, rotating means for polishing said space-bands, and a source of power for reciprocating said feed bars and rotating said polishing means whereby said space-bands will be exposed successively to said polishing means.

25 3. In a device of the class described an assembling container for space-bands, a vertical ridge on the inside of the end wall thereof for engagement between the feet of the space-bands as they fall therein, a pair of oppositely disposed, 30 abutments on the inner walls of said container, arcuately convex upper surfaces of said abutments for guiding the space-bands successively into stacked relation.

MONICA ROCK, 35
Executrix of the Estate of Arthur A. Rock,
Deceased.
